UNITED STATES PATENT OFFICE.

ALFRED W. GREGG, OF CHICAGO, ILLINOIS, ASSIGNOR TO WHITING CORPORATION, OF HARVEY, ILLINOIS, A CORPORATION OF ILLINOIS.

ELECTRODE HANDLER.

Application filed July 16, 1921. Serial No. 485,176.

To all whom it may concern:

Be it known that I, ALFRED W. GREGG, a citizen of the United States, residing at Chicago, in the county of Cook and State of Illinois, have invented a certain new and useful Improvement in Electrode Handlers, of which the following is a specification.

In electric melting furnaces now in common use, for instance the one which is exemplified in my prior companion application Serial No. 485,175, filed July 16, 1921, electric current is conveyed into and returned from the furnace thru comparatively large and heavy carbons extending thru the top of the furnace to the arcing point, within the furnace, which provides heat for melting the metal, and this invention relates to mechanism located outside of such a furnace for conveniently handling these heavy carbons while in the act of so conveying electric current.

The object of this invention is to provide a device of this class which can be easily and cheaply built and which the operator can readily operate to adjust the carbons to the requirements of the furnace.

The invention consists in means for obtaining the foregoing objects and in numerous features and details of construction hereinafter more fully set forth in the specification and claims.

Referring to the drawings in which like numerals designate the same parts throughout the several views.

Figure 1 is a side elevation partially in section of mechanism illustrating this invention in its preferred form.

Figure 2 is a plan view of the pulley mechanism shown at the right hand upper corner of Figure 1.

Figure 3 is a side view of the mechanism of Figure 1 looking at it from the right hand side.

Figure 4 is a general plan view of the furnace equipped with the mechanism of this invention.

Figure 5 is a detail plan view of one of the carbon carrying crane arms at approximately the line 5—5.

As fully set forth in detail in said prior application, the furnace includes a box member 10, hearth 12, a central island 14 and removable arched roof 16. In a furnace of this type in which the island 14 is oval, there

22 entering the roof 16, preferably thru water cooling rings 24 to carry electric current into and away from the furnace at the point 26 at the lower end of each carbon where it approaches a bed of carbon 28 supported by the island 14.

As in every electrical device where an arc is produced, the carbons entering the furnace have to be continuously fed into the arc area and there burned up. The problem to be solved is to provide a convenient means for supporting each of the carbons 18, 20 or 22, in the arcing area 26 adjacent to the carbon 28 and to, by feeding it down, maintain that relationship between the parts as the arcing continues. That is to say to maintain close and easy adjustment of electrodes under all conditions.

The preferred mechanism includes a vertical tubular post or mast 30 opposite to the carbon which is to be moved, suitably secured on the outside of the furnace box 10 by suitable brackets 32 and 34. Rotatably mounted on the upper end of this tube 30 is a frame work or head 36 traversed by parallel shafts 38, 40, 42 on which are journaled sets of wheels 44, 46 and a single wheel 48, the latter adjacent to a perforation 59, thru which passes a tension member or rope 52 on one of whose ends is a counter head 54 reciprocatable inside post 30. This rope 52 passes from counterweight 54 over one each of the pulleys 44, and 46 and thence downward to a suitable fastening device 56 on an arm 58 somewhat resembling a jib crane. Also attached to the fastening device 56 is another rope 60 passing up over another set of pulleys 44—46 and pulley 48, and thence extends downward around a winding drum 62 suitably mounted on a bracket 64 on the side of support 34 and thence upward to a hook 65 on the underside of frame 74. Rigid with this drum 62 is a gear wheel 66 engageable by a ratchet dog 68 carried by the frame 64 and also engageable by a conventional ratchet driving mechanism 70 operatable by a hand lever 72. When the operator moves the handle 72 in one direction he rotates drum 62 to wind up rope 60 and thus lift member 58, opposite movement being prevented by ratchet dog 68. When ratchet dog 68 is released the weight of member 58 and parts attached to it will normally carry it downward while the rope 60 unreels from drum 62. If there

is any stick in operation the operator may force it down by moving handle 72 in the proper direction.

- Rigidly supporting member 58 is a triangular frame 74, rotatable about post 30 and carrying two pairs of rollers 76 and 78, one roller of each pair located on an opposite side of and bearing against the post 30 in such position that the combination of rollers 10 properly support any load carried by member 58 from this vertical post 30. On the outer end of arm 58 and insulated therefrom at 79 is a horizontally extending clamping member 80 supplied with electric current 15 thru wire 82 leading to any suitable source thereof. In the conventional device of the drawing the clamp is effected by tightening the bolt 84.

In the operation of the device one such 20 carbon handler is provided for each carbon which enters the furnace. The operator, after having clamped a carbon in clamp 80, lowers it thru the water cooler 24 and the perforation 86 in roof 16 until it contacts 25 with carbon 28. The operator then operates handle 72 to slightly raise the member 58 and consequently the carbon until arcing space 26 is formed. Thereafter as the arc burns he manipulates dog 68 and lever 72 to properly 30 lower the carbon to maintain the arc.

When it is necessary to remove the furnace cover 16 the rotating of the frame 36 and of the member 58 about the column 30 makes it possible to swing everything out of the 35 way.

Having thus described my invention, what I claim as new and desire to secure by Letters Patent, is:

1. In mechanism of the class described, an 40 electric furnace, a carbon entering the furnace, a hollow post at the side of the furnace, a lifting member reciprocably and rotatably mounted on the post, means on the lifting member for attaching it to the carbon, a frame 45 rotatable on the post above the lifting member, sets of pulleys on the frame, a counter weight in the post, a tension member extending from the lifting member, over one set of said pulleys to said counterweight, 50 another tension member leading over other of said pulleys to the lifting member, and means manually controllable for operating the first tension member to effect raising

and lowering of the lifting member and attached carbon. 55

2. In a device of the class described, a stationary post, a load carrying member reciprocable and rotatable on the post, a counterweight reciprocable of the post, tension means connecting the weight to the load carrying member, another tension member connected to the load carrying member, means manipulating the last tension member to cause movement of the load carrying member, and means supporting the two tension members, intermediate of their ends from the post to permit rotation of the load carrying member about the post. 60

3. In a device of the class described, a stationary post, a load carrying member, reciprocable and rotatable on the post, a counterweight reciprocable inside the post, tension means connecting the weight to the load carrying member, another tension member connected to the load carrying member, means manipulating the last tension member to cause movement of the load carrying member, and means supporting the two tension members, intermediate of their ends from the post to permit rotation of the load carrying member about the post. 65

4. In mechanism of the class described, an electric furnace, a carbon entering the furnace, a post at the side of the furnace a lifting member reciprocably and rotatably mounted on the post, means for attaching the lifting member to the carbon, a frame above the lifting member, rotatable on the post, anti-friction devices on the frame, a counterweight reciprocable of the post, a tension member extending from the lifting member over one set of said anti-friction devices to said counterweight, another tension member leading over other of said anti-friction devices to the lifting member, and means manually controllable for operating the first tension member to effect raising and lowering of the lifting member and attached carbon. 80

In witness whereof, I have hereunto subscribed my name in the presence of two witnesses. 85

ALFRED W. GREGG.
